UNITED STATES PATENT OFFICE.

DE BERT HARTLEY, OF CHICAGO, ILLINOIS.

KITCHEN UTENSIL.

Application filed June 9, 1922. Serial No. 567,128.

To all whom it may concern:

Be it known that I, DE BERT HARTLEY, a citizen of the United States, and resident of Chicago, in the county of Cook and 5 State of Illinois, have invented a certain new and useful Improvement in Kitchen Utensils, of which the following is a full, clear, concise, and exact description, reference being had to the accompanying drawings, forming a part of this specification.

This invention relates to a combination can opener and sharpening device.

One of the features of the invention is the arrangement of the sharpening device 15 at an angle to the bar forming the body portion of the tool so as to permit the use of the sharpening device while the tool is hanging from a nail in the wall. This arrangement of the sharpening device at 20 the end of the tool also provides a more convenient handle for the device when it is used as a can opener.

Another feature of the invention closely related to the one just mentioned is that the 25 angular relation of the sharpener frame to the bar of the tool permits the surface of the bar being used as a guide for a shears or scissors blade to insure the shears blade engaging the sharpening member at the 30 right angle.

Other features and advantages will appear as the description of the invention progresses.

In the drawings,

35 Figure 1 is a perspective view of the device supported from a nail projecting from a wall or other surface;

40 Figure 2 is a perspective view of the device and shows the manner of using it to sharpen scissors;

Figure 3 is an end view of the sharpening device, and

Figure 4 is a section on the line 4—4 of Figure 1.

45 Referring now to the drawings, 10 indicates the bar of the tool which is provided at one end with the offset point or spur 11. The bar 10 adjacent to the spur 11 is provided with an opening 12 adapted to receive a nail or screw 13, by means of which the device may be supported on the wall.

50 Slidably mounted on the bar 10 is a collar 14 formed of a piece of sheet steel, the opposite ends 15 of which are rebent about the bar 10. Carried by the collar 14 is a knife or cutting member 16 which is pref-

erably formed by being punched from the face of the collar 14.

The bar 10 at the end remote from the spur 11 is arranged to provide a mounting 60 for the cutting element 17 of the sharpening device. The member 17 is formed as a prism and is an equi-angular triangle in cross section. The supporting framework for the member 17 is preferably formed 65 integral with the bar 10, and consists of the side members 18 and 19, which are connected by the three integral webs 20, 21 and 22. The connecting webs 20 and 22 are depressed, as seen in Figure 1, while the 70 web 21 is slightly raised, as viewed in this figure, thus permitting the insertion of the member 17 therebetween. A set screw 23 is provided in the web 21 which is arranged 75 to forcibly engage the cutting member 17 and retain it in position. It is to be noted that the members 20 and 22 are formed intermediate of the side members 18 and 19 into substantially V-shaped depressions 80 so as to receive one of the edges of the cutting member 17. The tie member 21 is formed with a substantially flat surface so as to engage one of the flat sides of the member 17. The side members 18 and 19 adjacent to their free ends diverge somewhat 85 so as to provide substantially V-shaped openings between the ends of the members 18 and 19 and the cutting member 17.

In the use of the device as a can opener, the spur 11 is inserted through the end of 90 the can near the center, and the sleeve 14 is adjusted along the bar 10 so that when the device is brought into engagement with the end of the can, the blade 16 will pierce the end of the can adjacent to the side 95 thereof. Using the members 18 and 19 as a handle, the device is then rotated about the spur 11, the blade 16 operating to cut the end from the can. The tin adjacent to the outside of the can is depressed during this 100 process so that no ragged or sharp edge projects inwardly towards the center of the opening. The members 18 and 19 being arranged at an angle of substantially 45° to the plane of the bar 10 provide a more 105 convenient handle than would be the case if they were not turned at an angle.

When the device is not in use, it may be supported from a nail or screw 13 projecting from the wall or other convenient surface.

When it is desired to use the device for

sharpening a kitchen knife, the blade of the knife to be sharpened is placed in the V-shaped opening between the end of the member 19 and the cutting member 17, and 5 the blade is drawn from the heel to the point. The position of the blade in relation to the sharpener is shown in Figure 1. Then the process is repeated, placing the blade in the opening between the member 10 18 and the member 17. The member 17, being of highly carbonized steel, operates to plane a thin layer off the blade adjacent to the edge thereof. This process of placing the blade first in one V-shaped opening 15 and then in the other, and drawing the blade from the heel to the point may be repeated as many times as is necessary to produce a good cutting edge on the blade. It is to be noted that the arrangement of 20 the sharpener at an angle to the supporting bar causes the edge of the knife to be disposed at an angle to the sharpener while occupying a position substantially parallel to the bar, thus producing a draw cut on 25 the knife edge.

In using the device as a knife sharpener, it is not necessary to remove it from its supporting nail 13. In fact, the device may be best used when longitudinal movement 30 of the bar 10 is prevented by the opening 12 thereof being in engagement with the nail 13. This arrangement makes the sharpening of the knife easier, and also lessens materially the danger of the operator cutting his or her hand during the 35 process.

If desired, the bar 10 may be laid flat on a table or bench and the sharpening device used in the same manner as though it were 40 supported on the wall. Preferably the opening 12 will be placed in engagement with a projection as 13 from the table to prevent longitudinal movement of the bar 10 during the sharpening process.

45 Due to the manner in which the sharpening member 17 is retained in position, it may be adjusted longitudinally or changed end for end, or taken out and rotated, thus providing an almost unlimited number of 50 different cutting positions.

The sharpening device may also be employed to sharpen shears or scissors. In using the device for sharpening shears, the cutting member 17 is first moved longitudinally until it projects beyond the bar 10; then the inner plane surface of the blade is placed in contact with the surface of the bar 10, as indicated in Figure 2, and the blade is drawn from the heel to the point 55 60 while being held firmly in engagement with the edge of the cutting member 17. In order to sharpen the other blade of the shears, it is held in a similar manner in

engagement with the bar 10 and drawn across the edge of the member 17. 65

It will thus be seen that the arrangement of the supporting framework for the cutting member 17 at an angle to the bar 10 provides a number of advantages. It permits the sharpening device to be used to 70 sharpen knives without removing it from its supporting nail on the wall. It not only permits the device to be used without removing it from the wall, but makes the use of the device easier than though the 75 sharpening member projected in the same plane as the bar 10. The arrangement of the members 18 and 19 at an angle to the bar 10 also acts to provide a more 80 convenient handle when the tool is used as a can opener. Furthermore, the angular arrangement of the cutting device permits it to be used to sharpen scissors during which process the bar 10 acts as a guide to insure that the scissors blade will engage the cutting member at the proper angle. 85

While in the above description and in the drawings certain definite details have been disclosed, it is to be understood that applicant contemplates slight variations in the 90 details of the device, and the invention, therefore, is to be limited by the scope of the appended claims.

Having now described my invention, what I claim is new and desire to secure by Letters Patent of the United States is:

A sharpening utensil comprising an elongated handle portion of sheet metal provided at one end with a hole for engagement of the handle portion with means to 100 secure it to a wall, claw members integral with the opposite end thereof and at an angle thereto, the said claw members diverging at their ends; a series of straps integral with said claw members and bridging the space therebetween, the said straps being alternately bent in opposite directions; one of said straps being formed with a plane surface and the others being of angle shape, the said first-mentioned strap being formed with a threaded opening for the reception of a clamping screw; a clamping screw; and a sharpener bar of triangular cross-section having its edge supported by 105 said angularly formed straps and its upper flat surface clamped down by said clamping screw to hold it fixedly in any one of a plurality of positions between said claw members. 110

In witness whereof, I hereunto subscribe my name this 3rd day of June, 1922.

DE BERT HARTLEY.
